(57) **CLAIM**

The ornamental design for a measurement portion of cocktail shaker, as shown and described.

DESCRIPTION

FIG. 1 is a bottom, front perspective view of a measurement portion of cocktail shaker;

FIG. 2 is a front view thereof, the rear view being a mirror image;

FIG. 3 is a right side view thereof, the left side view being a mirror image;

FIG. 4 is a top view thereof;

FIG. 5 is a bottom view thereof;

FIG. 6 is a cross-sectional view thereof taken along cross-section 6-6 of FIG. 5;

FIG. 7 is a cross-sectional view thereof taken along cross-section 7-7 of FIG. 5; and,

FIG. 8 is an exploded bottom, front perspective view of a cocktail shaker.

All broken lines of the measurement portion of cocktail shaker represent unclaimed features of the article to which the design is applied. The broken line showing of the lid of a cocktail shaker and the lower portion of the cocktail shaker of FIG. 8 are for environment and form no part of the claimed design.
